US0D1071181S

(12) **United States Design Patent** (10) **Patent No.:** **US D1,071,181 S**
(45) **Date of Patent:** **** Apr. 15, 2025**

(54) **URINARY INCONTINENCE DEVICE**

(71) Applicant: **Liv Labs Inc.**, Wilmette, IL (US)

(72) Inventors: **Carly R. Price**, Belmont, CA (US);
Eric J. Price, Belmont, CA (US);
Melody A. Roberts, Wilmette, IL (US);
Ruth E. Beeby, Santa Clara, CA (US)

(73) Assignee: **Liv Labs Inc.**, Chicago, IL (US)

(**) Term: **15 Years**

(21) Appl. No.: **29/835,619**

(22) Filed: **Apr. 20, 2022**

(51) **LOC (15) Cl.** **24-04**

(52) **U.S. Cl.**

USPC **D24/122**

(58) **Field of Classification Search**

USPC D24/127, 128, 108, 111, 121-125, 224,

D24/215

CPC A61F 2/005; A61F 2/0009; A61F 2/0036;

A61N 1/36007

(57) **CLAIM**

The ornamental design for a urinary incontinence device, as shown and described.

DESCRIPTION

FIG. 1 is a perspective view of a first embodiment of a urinary incontinence device showing the new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of a second embodiment of a urinary incontinence device showing the new design;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.
